UNITED STATES PATENT OFFICE

2,636,556

WINDOW BLIND

Aaron Lia Light and Morris Fine, Chicago, Ill.

Application February 23, 1950, Serial No. 145,779

7 Claims. (Cl. 160—11)

1

This invention relates to window blinds of the generally Venetian blind type, and particularly to a new and novel form of adjustable Venetian blind.

Venetian blinds of the well-known type are provided with a plurality of horizontal superposed strips of material mounted for rotational movement simultaneously around their longitudinal axes. Mechanism is usually supplied for the purpose of raising and lowering the blind so that when the blind is elevated the plurality of horizontal strips become grouped together at the top of the blind. Blinds of this type have certain inherent disadvantages which include the difficulty of cleaning, the expense involved in adapting the blinds to windows of various widths, and the mechanism involved is usually expensive.

The Venetian blind of the present invention is provided with a plurality of vertical positioned strips of material in overlapping relation, and one of the principal objects of the invention is to overcome the disadvantages inherent in the present known type of blind as enumerated above.

Another object of the invention is to provide a Venetian blind wherein a plurality of vertical strips of material are positioned in overlapping relation and which may be rotated about both ends thereof simultaneously to move the strips between open and closed positions.

A further object of the invention is to provide a Venetian blind wherein a plurality of overlapping vertically positioned strips of material are adapted to be wound around rollers positioned at the ends thereof thereby to permit the blind to be raised or lowered. In order that the strips may be overlapping, the rollers are located at the bottoms of alternate strips and at the tops of the other alternate strips.

Still another object of the invention is to provide a Venetian blind with a plurality of vertical overlapping strips of material, wherein the rollers at opposite ends of alternate strips have affixed thereto wiping members between which the strips are located, so that when the blind is raised or lowered the accumulated dust and dirt on the strips will be removed by the action of the wiping members, whereby the blind will be self-cleaning.

A still further object of the invention is to provide a Venetian blind having a plurality of overlapping strips of material, wherein each strip and its attached roller and rotating mechanism, may be applied separately as a unit, whereby the width of the window will determine the number of units to be used in any particular case.

2

Still another object of the invention is to provide a Venetian blind having a plurality of overlapping vertical strips of material wherein mechanism is provided to lower the blind from the top as well as to raise the blind from the bottom.

Still another and more specific object of the invention is to provide a Venetian blind having a plurality of overlapping vertical strips of material wherein mechanism is provided at the top and bottom of the blind for rotating the individual strips simultaneously about their longitudinal axes and wherein a single operating lever arm may be manually controlled for actuating the rotating mechanism at the top and bottom.

Other objects and advantages of the invention will become apparent upon reading the following description taken in conjunction with the accompanying drawings in which:

Fig. 1 is an enlarged elevational view of a Venetian blind in accordance with the present invention with certain parts broken away for the sake of clarity;

Fig. 2 is an elevational view of the blind illustrating its appearance when lowered from the top;

Fig. 3 is a view similar to Fig. 2, but showing the appearance of the blind raised from the bottom;

Fig. 4 is a horizontal sectional view through the assembled blind showing the individual strips thereof in partially rotated position;

Fig. 5 is a perspective view of one of the sections of the supporting plate on which the individual strips and rollers are mounted;

Fig. 6 is an enlarged fragmentary horizontal sectional view similar to Fig. 4, but showing the rotating mechanism as it appears when the vertical strips have been moved to closed position;

Fig. 7 is a vertical sectional view taken along the plane of line 7—7 of Fig. 6;

Fig. 8 is a perspective view of one of the roller devices; and

Fig. 9 is a longitudinal sectional view through one of the rollers.

Referring now more particularly to the drawings and especially to Fig. 1, the numeral 1 represents in general a window frame to which the Venetian blind of the present invention may be applied. The window frame is provided with the usual sides 2 and 3, the top 4 and bottom 5. The blind is adapted to be inserted within the confines of the window frame, and is provided with a plurality of strips of material identified by the numeral 6 and a plurality of alternate strips identified by the numeral 7.

Each of the alternate strips 6 is provided at

its lower end with a roller member 8 provided with a suitable frame in which the roller is mounted and with a pinion 9 on the underside thereof. The upper end of each of the alternate strips 6 has affixed thereto an elongated pin 10 provided with a pinion 11 at the upper end thereof.

Each of the alternate strips 7 has a roller 12 at the upper end thereof provided with a pinion 13. The lower end of each alternate strip 7 has a pin 14 affixed thereto which pin is provided with a pinion 15 at its lower end. Since the rollers 8 and 12 are substantially the same width as each of the strips 6 and 7, it is necessary to position these rollers at opposite ends of alternate strips in order that the strips themselves may overlap when in closed position.

The rollers and rotating mechanism at the upper part of the blind are shielded from view by a housing structure which includes a horizontally positioned plate 16 and a vertically positioned cover plate 17 extending downwardly therefrom. The pinions 11 and 13 at the top of the blind are suitably secured to the plate 16 by means of suitable pivot pins 18.

The rollers and rotating mechanism at the bottom of the blind are likewise concealed by means of a bottom plate 19 and a front cover plate 20 extending upwardly from the forward edge thereof. The pinions 9 and 15 which form a part of the rotating mechanism at the bottom of the blind are mounted by any suitable means in the bottom plate 19.

A guide strip 21 is located at each side of the window frame for the purpose of guiding the blind when it is raised or lowered. The guide strip 21 is adapted to cooperate with suitable rollers 22 at each side of the top and bottom cover plates so that when the blind is raised or lowered the guide strips 21 will form a track on which the rollers 22 will ride. It will be evident that the specific form of guide means may be varied as long as it serves the purpose of guiding the blind in its vertical movements. Ears 23 and 24 affixed to the top cover plate 16 are adapted to have secured thereto cords 25 and 26. These cords pass around the respective pulleys 27 and 28 located at the top of the window frame. The cords 25 and 26 then extend outwardly at one side of the blind and around a pulley 29 with the ends thereof hanging downwardly and available to be grasped for the purpose of lowering the blind from the top. Any suitable form of locking mechanism common in Venetian blinds may be used in connection with the pulley 29. The locking mechanism is adapted to be released upon manipulation of the cords 25 and 26 whereupon gravity will permit the top part of the blind to be guidingly lowered along the guide members 21. Each of the roller members 8 and 12 is provided with a spring so that when the top of the blind is lowered the rollers will cause the individual strips to be wound thereon.

The bottom plate 19 has a cord 30 affixed thereto which is adapted to pass through a locking mechanism 31 of any suitable and well-known type. The springs in the rollers 8 and 12 will have a tendency to draw the upper and lower ends of the blind together. The locking mechanism 31 at the bottom of the blind through which the cord 30 passes is adapted to maintain the bottom of the blind in its lowered position. When the cord 30 is manipulated to release the locking mechanism 31, the force of the springs in the respective rollers 8 and 12 will cause the bottom

end of the blind to be elevated. The appearance of the blind when the top part is lowered and when the bottom part is raised will be like that shown in Figs. 2 and 3, respectively.

Fig. 9 illustrates one of the rollers, and since all of the rollers have similar construction, a description of one will suffice for all. The roller of Fig. 9 indicated generally by the numeral 12 is generally tubular in shape and is closed at one end by a removable plate 32. The roller has a shaft 33 passing therethrough to which is affixed a coil spring 34. The outer ends of the shaft 33 are mounted in ears 35 formed as an integral part of each end 36 of a frame 37 (Fig. 8). The pinions 9 and 13 are affixed to the respective lower and upper rollers 8 and 12 so that when the pinions are caused to rotate, the roller attached thereto will also have a rotative movement.

The bottom plate 19 has an elongated rack 38 mounted thereon and extending along the rear edge thereof. This rack 38 is in mesh with all of the pinions 9 and 15 fixed respectively to the rollers 8 and pins 14. The rack 38 is mounted for longitudinal movement and the operation thereof may be more clearly understood by viewing Figs. 4 and 6. It will be evident that when the rack 38 is caused to move longitudinally, it will impart a rotative movement to all of the pinions 9 and 15 and cause the strips of material associated therewith to be rotated about their longitudinal axes. In order to move the rack 38 longitudinally, there is provided a gear member 39 mounted for rotation about a pivot 40 on the bottom plate 19. The gear 39 has an arm or handle portion 41 extending forwardly through a suitable opening in the bottom front cover plate 20. The gear 39 is in mesh with the pinion 9 and when it is caused to rotate by manual movement of the arm 41, it will, in turn, cause the pinion 9 to rotate thereby imparting a longitudinal movement to the rack 38. As explained previously, this movement of rack 38 will also rotate the other pinions 9 and 15 in mesh therewith to cause a rotative movement of the individual strips 6 and 7.

Another pinion 42 is positioned adjacent the gear 39 and is in mesh therewith. The pinion 42 has a rectangular opening therein adapted to receive a vertical rod or bar 43 which extends from the bottom 5 of the window frame through the bottom plate 19 upwardly through the top plate 16 to the top 4 of the window frame. A second pinion 44 is mounted for rotation in a suitable bracket affixed to the underside of the top plate 16 and also has a rectangular opening therein adapted to receive the rectangular rod or bar 43. The pinion 44 is directly in mesh with a gear 45 also mounted for rotation on the underside of the top plate 16. The gear 45 meshes with the pinion 11 which, in turn, is in mesh with a longitudinally reciprocating rack 46. All other of the pinions 11 and 13 at the top of the blind also mesh with the rack 46 so that longitudinal movement thereof will rotate these pinions thereby causing the top part of each vertical strip 6 and 7 to rotate about the longitudinal axis thereof. When the arm 41 is manipulated to open or close the vertical strips, the rotation of gear 39 will rotate pinion 42. This will, in turn, cause the vertical bar 43 to rotate as well as the pinion 44 adjacent the top end thereof. Rotation of the pinion 44 will rotate the gear 45 and pinion 11 to reciprocate the upper rack 46 at the same rate and for the same distance as the bottom rack 38. Thus a rotating mecha-

nism is provided at both the upper and lower ends of each of the strips 6 and 7 to overcome any twisting of the strips when they are moved between open and closed positions.

Figs. 2 and 3 illustrate that the vertical connecting bar 43 is stationary except for its rotative movement, and when the top or bottom end of the blind is lowered or raised, these ends will move with respect to the bar 43.

Figs. 8 and 9 illustrate the details of the respective rollers 8 and 12, and it has been pointed out hereinbefore that the rollers are each mounted in a frame such as shown at 37 in Fig. 8. The identical frame is used for both the upper and lower rollers by merely reversing the position thereof as may be clearly seen in Fig. 7. The frame 37 is generally U-shaped and is provided with the spaced vertically extending legs 36. The opposite ends of the legs 36 are connected together by straps 47 and 48 which are located in spaced apart relation. The inner opposed edges of these straps 47 and 48 are provided with wiping members 49 and 50. The strip of material which is wound around the roller is adapted to pass through the frame and between the wiping members 49 and 50 which may be formed of any suitable relatively soft material such as felt, or the like. The wiping action of these members on the individual strips 6 and 7 will take place whether the top of the blind is lowered or the bottom of the blind is raised. Thus, the blind of the present invention has the unique feature of being self-cleaning.

A further advantage in the self-cleaning feature resides in the easy replacement of the wiping members when they become worn or dirty because the straps 47 and 48 to which they are affixed may be easily removed from the frame 37. Either or both of the straps 47 and 48 may be removed and replaced by other straps having new wiping members attached thereto.

A further feature of the invention resides in the ease with which the blind may be adjusted for windows of various widths. As explained above, each strip of material together with its attached roller and the pinions 13 and 15 constitutes a unit by itself. Thus, the upper plate 16 and bottom plate 19 each constitute a plurality of individual sections such as that indicated by the numeral 51 in Fig. 5. Each section embodies a base portion 52 with upwardly extending flange portions 53 and 54 at the rear and front thereof, respectively. The front flanged portion 54 has a slot extending the length thereof substantially in the form of a keyhole as shown at 55. One end of the flange portions 53 and 54 has a pin 56 extending outwardly therefrom. Each pin is adapted to be received within a corresponding recess 57 in the adjacent section. This bottom section, as shown in Fig. 5, is identical with the corresponding sections comprising the top plate 16, as may be seen in Fig. 7. The rollers 12 with the strip of material 7 wound thereon is affixed to an upper section with its pinion 13. The pin 14 affixed to the opposite end of the strip 7 is then assembled with the pinion 15 thereon to a bottom section like that shown in Fig. 5. Depending upon the width of the window, any suitable number of these units may be placed side by side after which a cover plate or valance 17 is assembled with the upper sections and a similar cover plate or valance 20 is assembled with the lower sections. Each of the cover plates 17 and 20 is provided with a rearwardly extending flange having a bead

thereon adapted to fit into the elongated keyhole slot of the individual sections. This construction enables all of the sections to be held together, and the only parts of the blind which may have to be cut to a predetermined length will be the cover plates 17 and 20.

All of the sections of the upper and lower plates are identical with the exception of the end section which receives the vertical bar 43, and which has the pinions 42, 44 and gears 39, 45 mounted thereon. These sections also have affixed thereto the guide rollers 22 which cooperate with the tracks 21 in guiding the blind when it is raised or lowered.

It will thus be evident that the blind embodying the present invention and the features as above outlined, will be less expensive to install than those in present use because it does not have to be custom made to the dimensions of individual windows. Regardless of the width of the window the required number of sections or units may be assembled together to accommodate the desired width. It is likewise true that the height of the window is of little importance because the length of the individual strips 6 and 7 can all be made to accommodate the longest window if the blind is to be applied to a window of lesser height, then the extra length of the strips will merely be wound around the respective rollers.

There is also relatively little in the way of installation because the only fixtures to apply will be the vertical bar 43, the pulleys 27 and 28, the locking pulley 31 and the guide tracks 21. All other parts of the blind are movable with respect to the window frame, and, therefore, need not be affixed thereto.

Fig. 1 of the drawings illustrates the blind installed and in fully closed position with the individual strips of material in overlapping relation and the upper and lower ends thereof fully extended. When it is desired to open the blind by rotating the individual strips, it is merely necessary to actuate the arm 41 which will reciprocate the lower rack 38 and the upper rack 46. This movement of the racks in mesh with the respective pinions will cause a simultaneous rotation of all strips about their longitudinal axes. The blind may be lowered from the top by merely releasing the locking mechanism 31 associated with the upper cords 25 and 26, whereupon gravity will permit the upper part of the blind to move downwardly along the guide tracks 21. The lower end of the blind may be raised by releasing the locking mechanism 31 associated with the cord 30, whereupon the springs 34 within each of the roller members will exert a force sufficient to raise the blind. This action of raising the lower end and of lowering the upper end may be performed as shown in Figs. 2 and 3, or the upper and lower ends may be moved together simultaneously if so desired. This action of raising and lowering the blind may also take place whether the blind strips themselves are in open or closed positions. It is likewise true that the rotation of the strips to open and closed positions may take place even though the bottom of the blind is in raised position or the top of the blind has been lowered.

The raising and lowering of the blind will also automatically clean the individual strips due to the action of the replaceable wiping members 49 and 50.

While the invention has been described herein with particular respect to vertically posi-

tioned strips of material, it will be evident that if the occasion arises the same device may be installed in a window frame so that the strips are horizontal. The rotating mechanism will still function in this position to open and close the strips and the opposed ends of the blind may be moved toward each other as desired due to the force of the springs within the roller members.

Changes may be made in the form, construction and arrangement of parts from that disclosed herein without in any way departing from the spirit of the invention or sacrificing any of the attendant advantages thereof, provided, however, that such changes fall within the scope of the claims appended hereto.

The invention is hereby claimed as follows:

1. A window blind comprising a plurality of adjacent strips of flexible material positioned in overlapping relation when closed, roller means at the opposite ends of adjacent strips on which the strips may be rolled, whereby the rollers on alternate strips will be at the same ends thereof, means at each end of each strip for mounting each strip for rotation about the longitudinal axis thereof, and mechanism for rotating all of said strips and rollers simultaneously about their axes at both ends thereof for moving the strips to open position.

2. A window blind comprising a plurality of vertically positioned strips of flexible material located in overlapping relation when closed, a roller at the top of each alternate strip and at the bottom of each other alternate strip on which the strips are adapted to be wound when the blind is raised or lowered, means to raise the bottom of the blind, and other means to lower the top of the blind.

3. A window blind comprising a plurality of vertically positioned strips of flexible material located in overlapping relation when closed, a roller at the top of each alternate strip and at the bottom of each other alternate strip, said strips adapted to be wound on said rollers when the blind is raised or lowered, a top plate and a bottom plate on which the respective upper and lower rollers are mounted, thereby to provide upper and lower assemblies, guide means along each side of the blind, other guide means on said top and bottom plates cooperating with said first guide means, means to elevate the lower assembly along said guide means, and means to lower said upper assembly along said guide means.

4. A window blind comprising a plurality of vertically positioned strips of flexible material located in overlapping relation when closed, a roller at the top of each alternate strip and at the bottom of each other alternate strip,

said strips adapted to be wound on said rollers when the blind is raised or lowered, means to raise the bottom of the blind, means to lower the top of the blind, and wiper means on each of said rollers adapted to wipe clean the individual strips each time the blind is raised or lowered.

5. A window blind comprising a plurality of adjacent strips of flexible material positioned in overlapping relation when closed, rollers at the opposite ends of adjacent strips, said strips adapted to be wound on said rollers when one end of said blind is moved toward the other end thereof, means to move the ends of the blind 10 toward or away from each other, and wiper means associated with each of said rollers adapted to wipe clean the individual strips each time one end of the blind is moved toward or away from the other end.

15 6. A window blind comprising a plurality of individual sections, each of said sections including an elongated strip of flexible material and a roller at one end of said strip, and means for mounting a plurality of said sections on a common support at each end thereof with the rollers of adjacent strips at opposite ends thereof, whereby each support will be freely movable toward and away from the other support.

20 7. A window blind comprising a plurality of individual sections, each of said sections including an elongated strip of flexible material and a roller at one end of said strip on which said strip is adapted to be wound, wiper means associated with said roller and positioned in contact with both sides of said strip and adapted to wipe the surfaces of said strip when it is wound or unwound from said roller, and means for mounting a plurality of said sections on a common support 25 at each end thereof with the rollers of adjacent sections being located at opposite ends thereof, whereby each support will be freely movable toward and away from the other support.
